BRUSHMAKING MACHINE

John I. Carlson, Aurora, Ill., assignor to Carlson
Tool & Machine Company, a corporation of
Illinois

Application November 10, 1950, Serial No. 195,044

24 Claims. (Cl. 300—3)

1

This invention relates to brush making machines.

It is the general object of this invention to produce a new and improved brush making machine.

It is a more specific object of the invention to produce a brush making machine capable of operating continuously and automatically to drill holes in a brush back and to insert tufts in the holes without the necessity of being attended by an operator, the capacity of the machine for continuous production being limited only by the consideration of the size of the storage facilities for blank brush backs to be fed to the machine.

It is a further object of the invention to produce a brush making machine having means for automatically feeding blank brush backs to a conveyor which is adapted to convey brush backs to a drilling station whereat a plurality of holes are drilled, to a tufting station whereat a tuft is inserted in each hole, and then to a release station where the completed brush back is released from the conveyor, and in which the entire sequence of operations is automatically timed and performed.

Another object of the invention is to produce a brush making machine having a movable conveyor adapted to receive a brush back automatically delivered thereto from a storage means, and to convey the brush back to a drilling station having means for forming holes in the brush back, and to a tufting station having means for inserting tufts into the holes, and in which the conveyor is mounted upon a carrier movable in two directions substantially at right angles to each other and including means for moving the carrier in at least one of said directions each time a brush back is positioned at the drilling station, and at the tufting station and to provide means for intermittently moving the conveyor from one station to another after the completion of said predetermined operations.

Yet another object of the invention is to provide a completely automatic brush making machine having a drill for forming holes in a brush back, a tufter for inserting a tuft into said holes, and a movably mounted conveyor adapted to receive brush backs from a storage means to convey them to the drill, and then to the tufter, and finally to release the drilled and tufted brush backs and in which all of said operations are timed and actuated through the medium of a plurality of constantly rotating cams.

A further object of the invention is to provide in a brush making machine having a re-

2

ciprocating drill and tufter, a carrier adapted to carry a plurality of brush backs and means for moving said carrier in at least two directions substantially at right angles to each other through the medium of driven cams, movement of the carrier in at least one of said directions taking place each time the drill and tufter are reciprocated in order to drill a predetermined number of holes in each brush back while simultaneously inserting a tuft in each hole previously drilled in another brush back and to provide such moving means with easily, yet accurately operable adjustments, more accurately to locate the holes in each brush back.

Another object of the invention is to produce a new and improved mechanical neutralizing or centering means for the tuft guard in a brush making machine.

Other and further objects of the invention will be readily apparent from the following description and drawings, in which:

Fig. 1 is a front elevational view of a brush making machine embodying the invention;

Fig. 2 is a vertical sectional view of the central portion of Fig. 1, along line 2—2 thereof, showing the carrier and a part of the actuating means therefor;

Fig. 3 is a view of the back carrier shown in the central portion of Fig. 1;

Fig. 4 is a top plan view of the apparatus shown in Fig. 3;

Fig. 5 is a longitudinal sectional view of the right-hand end of the carrier shown in Fig. 1;

Fig. 6 is a view showing a modified form of the feeding mechanism for feeding brush backs to the carrier;

Fig. 7 is a top plan view, partly in section, of the mounting for the carrier and the means for moving the same, taken substantially along line 7—7 of Fig. 1;

Fig. 8 is a sectional view along line 8—8 of Fig. 7;

Fig. 9 is an enlarged detail vertical section showing the means for moving the carrier in one direction;

Fig. 10 is a sectional view of the carrier similar to Fig. 2 and showing means for moving the carrier in a vertical direction; and

Fig. 11 is a side elevation of the machine shown in Fig. 1.

While the invention is susceptible of embodiment in many different forms, there is shown in the drawings and hereinafter described in detail one specific embodiment, with the understanding that the present disclosure is to be considered as

In order more firmly to hold a brush back in the gripping means, there is secured to the upper surface of the ways 46 a guide member 51 provided with a projecting lip 52 adapted to project over the inner end of a brush back held in the gripping means. The lip 52 is provided with arcuately cut away portions 52a and 52b located at the drilling station A and the tufting station B in order to expose the tip of the brush back for the drilling and tufting operations. An additional guideway 53 is secured to the outer side plate 35 by means of the bracket 54 and is provided with a substantially U-shaped channel 55 adapted to receive the outer end of a handle portion 50a of the brush back. An additional guide member 56 is secured to the guide 51 by means of arms 57 and 58 and is adapted to hold the outer extremity of the portion of the brush back which is to be tufted in firm alignment.

It is, of course, understood that the various sizes and spacings shown for the blocks, jaws and guide means illustrated may be varied to accommodate brush backs of varying sizes and shapes. For the purpose of this disclosure, however, the brush back undergoing drilling and tufting is illustrated as a tooth brush.

The hopper 32 is, as previously stated, adapted to contain a plurality of blank brush backs and to this end is provided with side portions 60 and 61 (see Fig. 5) adapted to guidingly receive a plurality of blank brush backs 50 therebetween. In the particular embodiment shown in Fig. 5, it is contemplated that the brush backs will, by their own weight, feed themselves to the conveyor as it is moved therebeneath. Thus as the jaw 47b moves beneath the hopper to the position illustrated in Fig. 5, the blank brush back 50b drops down into the space between the jaws 47a and 47b. As the jaw 47a is moved to the position shown as occupied by the jaw 47b, the blank brush back 50c will drop down into the space between the jaw 47a and the following jaw 47c. It may be advantageous to provide a small rubber insert 62 on each of the jaws to provide a firmer grip on the brush backs.

A slightly modified form of hopper is illustrated in Fig. 6. As illustrated in that figure, there is shown a hopper 32' adapted to contain a supply of brush backs 50'. For the purpose of feeding brush backs to the conveyor the sides 60' and 61' of the hopper are so located as to guidingly receive the brush backs which are held in place by a guide bar 63. A pneumatically operated plunger is reciprocably mounted in a cylinder 64 connected by a pipe 65 to a source of compressed air and operated intermittently in timed relation with intermittent movement of the conveyor to force a brush back 50' from the hopper into the space between jaws on the conveyor. In this particular form of feeding means, it is advisable to provide a guide plate 66 to insure that brush backs are properly positioned on the jaws as they are fed through from the hopper.

As previously stated, the drill and tufter are reciprocated constantly to form holes in one brush back positioned at the drilling station and to insert and staple tufts in previously drilled holes in another brush back positioned at the tufting station. The forming of a predetermined plurality of holes and the spacing thereof is accomplished by moving the carrier in at least one direction each time the drill and tufter are reciprocated. When the predetermined number of holes have been drilled in a brush back, the conveyor is moved to position other brush backs at

the drilling and tufting stations in order that the cycle of drilling and tufting may continue uninterruptedly. Inasmuch as the drill and tufter may be reciprocated as rapidly as three or four times a second, it is clear that little time is provided for shifting the conveyor. To achieve the required rapid motion of the conveyor, there is provided a pneumatic piston and cylinder device 70 secured to the side plate 36 of the carrier and provided with a rod 71 secured to the piston and carrying a pawl 72 pivotally secured thereto and adapted to engage the teeth 73 of a ratchet wheel 74 fixedly secured to the shaft 75 which carries the sprocket 38. Reciprocation of the piston within the device 70 is adapted to move the rod 71 rightwardly from the position shown in solid lines in Fig. 3 to the position shown in dotted lines therein to rotate the ratchet wheel. A spring 76 is provided to insure proper engagement between the pawl and ratchet teeth and to this end has one end secured to the pawl 72 and the other end secured to an arm 77 secured to the side plate 36 and extending downwardly and providing a bearing for the shaft 75.

Because of the short time permitted for movement of the carrier between the reciprocatory cycles of the drill and tufter, the compressed air released into the piston and cylinder device 70 for reciprocating the piston must be under considerable pressure and, in effect, constitutes an explosive charge rapidly to move the conveyor. Obviously, when such an exceedingly rapid movement is achieved there is grave danger that the conveyor will overrun its desired position. Accordingly, additional means are provided to prevent the conveyor from travelling farther than the distance between the jaws on the conveyor in order to move the same only the distance required to move a brush back in each station out of that station while simultaneously moving other brush backs into the stations.

To that end, a second ratchet wheel 80 (see Fig. 4) is also secured to the shaft 75. A second pawl 81 is rotatably secured to a shaft 82 fixed to the inner side plate 36 and carries a pin slidable in an elongated slot 84 provided in an arm 85 secured to the ratchet wheel 74. A spring 86 has one end secured to the arm 77 and the other to the pin 83 constantly to urge the pin against the right-hand end (as shown in Fig. 3) of the slot 84 and yet to provide a resilient connection between the pin and slot. As the ratchet wheel 74 is rotated clockwise by the pawl 72, the arm 85 is carried rightwardly by such movement to draw the pawl 81 from the position shown in solid lines in Fig. 3 to the position shown in dotted lines therein wherein it engages the teeth 87 of the ratchet wheel 80. Such engagement, of course, effectively stops the rotation of the shaft 75 and prevents overrunning of the conveyor.

The rod 71 which connects the piston to the pawl 72 is adjustable in length so that the machine may be adapted to move the conveyor intermittently varying distances to accommodate the various sizes of brush backs to be operated upon. To this end the rod 71 is broken into the portions 71a and 71b with both portions having threaded ends adapted to be received in a nut portion 88 and a neck portion 89 of a unitary fitting which spans the space between the broken portions of the rod. The portions 71a and 71b, where they are received in the nut portion 88 and neck portion 89 respectively, carry opposite threads so that rotation of the nut portion serves

to increase or decrease the effective length of the rod and thus to increase or decrease the degree of rotation imparted to the ratchet 74 with reciprocation of the piston.

Compressed air is supplied to the piston and cylinder device through a line 90 (see Fig. 2) connected to a source of compressed air through the medium of a valve device 91. Obviously, the movement of the conveyor must be timed to coincide with the completion of the drilling of a predetermined number of holes in a brush back, and to this end the valve device is operated by means of a cam 92 secured to the main cam shaft 93. A cam follower 94 rides on the cam and is connected to a lever 95 pivotally mounted on the body portion 96 of the valve. The lever is provided with an actuating lug 97 adapted to contact a plunger 98 which operates the valve to admit compressed air into the cylinder to reciprocate the piston therein. An additional air line 99 may connect the valve device 91 with the cylinder 64 which contains the feeding plunger in the hopper illustrated in Fig. 6 in order that the plunger may apply pressure against a brush back in the hopper and slide it into the gripping means on the conveyor when the latter has completed its intermittent movement.

As previously indicated, the positioning of a blank brush back at the drilling station to form the desired number of holes in the brush back, properly aligned and spaced, and the positioning of a drilled brush back at the tufting station to bring sequentially, each of the previously drilled holes therein directly beneath the tuft for reception of a tuft, is accomplished by shifting the carrier in at least one direction each time the drill and tuft are reciprocated. To accomplish the movement of the carrier a first guideway 100 (see Figs. 2, 3 and 8) is mounted upon a pair of posts 101 and 102 vertically movable in sockets 103 and 104 formed in the frame 20. Compression springs 105 and 106 surrounds the rods 101 and 102 respectively and bear against the frame and guideway to cushion the movement therebetween and to assist in the vertical movement of the carrier when such movement is required as hereinafter explained. Lock nuts 101a and 102a are threadedly mounted on the lower ends of the posts 101 and 102, respectively, and may be tightened against the lower ends of the sockets 103 and 104 to prevent vertical movement of the carrier should the particular style of brush backs being operated upon require no such movement. The guideway 100 is positioned beneath and parallel to a line joining the drilling and tufting stations and slidably carries a member 107 for movement therealong. As best shown in Fig. 2, the member 107 is provided with depending sides 108 and 109, which engage the sides of the guideway 100, and with removable guide flanges 110 and 111 which extend beneath and engage the underside of step portions 112 and 113 formed in the guideway 100 in order to securely hold the member 107 on the guideway.

As shown in Figs. 7 and 8, the member 107 carries a pair of spaced parallel guideways 115 and 116 which extend at right angles to the guideway 100. The carrier 30 is provided with channels 118 and 119 adapted to slide on the guideways 115 and 116 with each of the channels being provided with side flanges 120 adapted to ride on the underside of stepped portions 121 formed in each of the guideways, as shown in Fig. 3. From the foregoing, it can be seen that movement in a direction parallel to a line joining

the drilling and tufting stations is accomplished by sliding the member 107, and hence the carrier 30, along the guideways 100 while movement at right angles thereto is accomplished by sliding the carrier along the guideways 115 and 116. Movement of the carrier in each or both of said directions is accomplished through constantly rotating cams on the main cam shaft of the machine.

For sliding the member 107 on the guideway 100 there is provided a plate 120 secured to the right-hand end of the member (as seen in Fig 7) and having an elongated opening 121 therein in which a bushing 122 is slidable. The bushing 122 is adapted to be secured to a post 123 fixed to crank means in the form of a rotatably mounted disc 124. In order to provide accurate means for adjusting the throw of the crank, the bushing 122 is eccentrically mounted on the post 123 and is secured thereto, by means of a knurled collar 125, in any position to which it may be rotated on the post. The disc 124 is provided with a post 126 which extends therebeneath and is received in a slot 127 formed in the outer end of a slide bar 128 slidably on the frame 20 of the machine. A spring 129 has one end affixed to an extension 130 of the post 126 and has its other end secured to the frame of the machine to urge the post into engagement with the slot 127 and to hold the cam follower attached to the slide bar 128 in contact with its actuating cam 132. The cam 132 serves, through the medium of the connecting means just described, to move the member 107 back and forth along the guideway 100.

The rear side plate 36 of the carrier is provided with an angle iron 140 (Fig. 2) which extends therealong. A second parallel angle iron 141 having an upstanding face 142 is secured in spaced parallel relation to the face 143 of the angle iron 140 by means of a plurality of posts 144 which extend therebetween. The faces 142 and 143 define an elongated slot 145 adapted to receive a post 146 eccentrically mounted on a pin 147 threadedly secured to a second slide bar 148. The post 147 may be secured in any one of three holes 147a, 147b or 147c, in the slide bar 148, roughly to position the carrier. The slide bar 148 is slidable in the frame and carries a cam follower 149 engaging a cam 150 fixed to the shaft 93. The post 146 may be rotated about the pin 147 accurately to position the carrier and then may be secured in any desired position thereon by tightening the pin 147 to bring the head 150 thereof into firm engagement with the bottom of a recess 151 in which it is received and formed in the top portion of the post 146. A spring 152 (see Fig. 9) has one end secured to the frame 20 and the other secured to a post 153 which extends through an opening 154 in the frame and is secured to the slide bar 148, the spring serving to urge the slide bar, and hence the cam follower, against the cam.

Occasionally, the brush back to be operated upon is provided with a surface which is non-planar. This requires that the carrier be moved not only horizontally but vertically. For effecting vertical movement of the carrier, the guideway 100 is provided with a pair of buttons 160 secured to the underside thereof (Fig. 10) adapted to ride on a pair of spaced camming surfaces 161 affixed to a plate 162. The plate 162 is, in turn, secured to the slide bar 148 by means of bolts 163 which extend through an opening 164 in slide cover plate 165. The camming surfaces 161 are

complementary in shape to the surface to be drilled and tufted in a brush back 50' on the conveyor. Movement of the carrier in a direction parallel to the curvature of the brush back 50' is accomplished by movement of the slide bar 148. Movement of the slide bar moves the camming surfaces beneath the buttons 160 and thus raises or lowers the carrier. Vertical movement of the carrier is permitted by the means previously described, that is, the provision of the posts 101 and 102 which are vertically movable in the sockets 103 and 104 in the base. Obviously, the particular shape of the camming surface 161 is determined by the shape of the brush back to be operated upon and should the latter have a plane surface the camming surfaces may be omitted.

It is contemplated that the brush making machine of this invention will be equipped with a tuft guard of the general type disclosed in said Patent 2,415,083. For that purpose, the shaft for oscillating or reciprocating the tuft guard is secured to a crosshead 170 which is adapted to be oscillated either clockwise or counterclockwise from the neutral position shown in Fig. 11. For oscillating the crosshead there is provided an arm 171 secured to a pin 172 mounted eccentrically on the driven gear 173. The arm carries a collar 174 resiliently held in the position shown by a spring 175 and adapted to be brought against the upper portion of the crosshead 170 to rock the same in a counterclockwise direction with rotation of the gear wheel 173. The arm 171 is slidable in a sleeve 176 secured to a crank 177 which is slidable in the crosshead. As the crank is moved to the opposite end of the crosshead 170, reciprocation of the arm 171 will, of course, rock the crosshead in a clockwise direction. Sliding of the crank 177 from one end to the other of the crosshead is accomplished through the crank and lever mechanism generally designated at 178, which includes a driven cam 179, a lever 180 pivoted to the frame and provided with a cam follower 181 riding on the cam and held thereagainst by means of a spring 182. A crossbeam 183 has one end pivotally connected to the lever 180 and its other end connected to a second lever 184 which carries a sleeve 185 slidably surrounding a control rod 186 and abutting against a spring 187. The other end of the spring 187 abuts a collar 188. The crank 177 is secured to the upper end of the rod 186, and hence movement of the rod through the cam and lever means 178 serves to move the crank from one end of the crosshead to the other. A spring 189 is secured to the frame and to the crosshead 170 to urge the same to return to the neutral position shown.

To assist the spring 189 in returning the crosshead to neutral, there is provided an arm 190 having one end pivotally secured to the frame at 191 and secured at an intermediate portion to a spring 192 attached to the frame. The upper end 193 of the arm has a flat face urged against a flattened portion 194 (Fig. 1) provided on a disc 195 secured to the shaft upon which the crosshead is mounted. Thus should the spring 189 fail to return the crosshead to exactly neutral position the pressure of the face 193 against the flattened portion 194 serves to rotate the disc to a position in which said portion along substantially its entire length is in contact with the upper flat face of the arm.

I claim:

1. In a brush making machine having a drilling station including a drill to form holes in a

brush back, a tufting station including a tufter to insert tufts into said holes and means for operating said drill and tufter to drill a hole in a brush back positioned at the drilling station while simultaneously inserting a tuft in a previously drilled hole in another brush back positioned at the tufting station, means for conveying brush backs to the drilling station and then to the tufting station comprising a carrier, means for moving the carrier in at least two directions substantially at right angles to each other, a conveyor movably mounted on the carrier and provided with a plurality of brush back gripping means, a feeding station including a hopper mounted on the carrier, means in the hopper for storing brush backs and for feeding brush backs to each of the gripping means as it is positioned at the feeding station, and means for intermittently moving the conveyor sequentially to position a gripping means at the feeding station to receive a brush back and then to move the conveyor to move the last-mentioned brush back sequentially to the drilling station and to the tufting station.

2. In a brush making machine having a drilling station including a drill to form holes in a brush back and a tufting station including a tufter to insert tufts into said holes, operating and conveying means comprising a carrier, a conveyor mounted on the carrier for movement in a path passing through the drilling station and the tufting station and provided with a plurality of brush back gripping means, a feeding station in said path including storage means mounted on the carrier for holding a supply of brush backs and adapted to feed a brush back into each gripping means as it passes the feeding station, means for alternately moving and halting the conveyor to move each gripping means into and halt it sequentially at the feeding station, the drilling station and then at the tufting station, and means operating automatically each time the conveyor is halted to operate the drill to form holes in a brush back in the gripping means at the drilling station and to operate the tufter to insert tufts into previously formed holes in another brush back held in the gripping means at the tufting station.

3. In a brush making machine having a drilling station including a drill to form holes in a brush back, a tufting station including a tufter to insert tufts into said holes and means for operating said drill and tufter to drill a hole in a brush back positioned at the drilling station while simultaneously inserting a tuft in a previously drilled hole in another brush back positioned at the tufting station, means for conveying brush backs to the drilling station and then to the tufting station comprising a carrier, means for moving the carrier in at least two directions substantially at right angles to each other, a pair of sprockets mounted in spaced relationship on the carrier for rotation in a single plane, a chain carried by the sprockets and having portions passing through the drilling station and the tufting station, a plurality of spaced jaws on the chain, means for feeding a brush back to the space between jaws and located at a point where said chain is travelling in an arcuate path around a sprocket whereby a brush back fed from the feeding means is gripped by the jaws as the chain travels in a linear path after leaving said sprocket, and means for intermittently rotating the sprockets to position a brush back held in

the jaws sequentially at the drilling station and then at the tufting station.

4. In a brush making machine having a drilling station including a drill to form holes in a brush back, a tufting station including a tufter to insert tufts into said holes and means for operating said drill and tufter to drill a hole in a brush back positioned at the drilling station while simultaneously inserting a tuft in a previously drilled hole in another brush back positioned at the tufting station, means for conveying brush backs to the drilling station and then to the tufting station, comprising a carrier, means for moving the carrier in at least two directions substantially at right angles to each other, a pair of sprockets mounted in spaced relationship on the carrier for rotation in a single plane, a chain carried by the sprockets and having portions passing through the drilling station and the tufting station, a plurality of spaced jaws on the chain, means for feeding a brush back to the space between jaws and located adjacent one of the sprockets where the chain is travelling there-around whereby a brush back fed from the feeding means is gripped by the jaws as the chain travels in a linear path after leaving said sprocket, a release station located adjacent the other sprocket and having means for receiving a brush back as it is released by said jaws as the chain travels in an arcuate path around said other sprocket, and means for intermittently rotating the sprockets to position said brush back sequentially at the drilling station and the tufting station and then to move the brush back to the release station.

5. In a brush making machine having a drilling station including a drill to form holes in a brush back, a tufting station including a tufter to insert tufts into said holes and means for operating said drill and tufter to drill a hole in a brush back positioned at the drilling station while simultaneously inserting a tuft in a previously drilled hole in another brush back positioned at the tufting station, means for conveying brush backs to the drilling station and then to the tufting station comprising a carrier, means for moving the carrier in at least two directions substantially at right angles to each other, a pair of sprockets mounted in spaced relationship on the carrier for rotation in a single plane, a chain carried by the sprockets and having portions passing through the drilling station and the tufting station, a plurality of spaced jaws on the chain, means for feeding a brush back to the space between jaws and located at a point where said chain is travelling in an arcuate path around a sprocket whereby a brush back fed from the feeding means is gripped by the jaws as the chain travels in a linear path after leaving said sprocket, and a pneumatic piston and cylinder device connected to one of the sprockets for intermittently but rapidly rotating the sprockets to position a brush back fed to the jaws by the feeding means sequentially at the drilling station and then at the tufting station.

6. In a brush making machine having a drilling station including a drill to form holes in a brush back, a tufting station including a tufter to insert tufts into said holes and means for operating said drill and tufter to drill a hole in a brush back positioned at the drilling station while simultaneously inserting a tuft in a previously drilled hole in another brush back positioned at the tufting station, means for conveying brush backs to the drilling station and then to the tuft-

ing station comprising a carrier, means for moving the carrier in at least two directions substantially at right angles to each other, a pair of sprockets mounted in spaced relationship on the carrier for rotation in a single plane, a chain carried by the sprockets and having a portion passing in a linear path through the drilling station and the tufting station, a plurality of brush back gripping means on the chain, spaced parallel ways on the carrier extending along said path on both sides of the chain, guide means secured to the chain and riding in said ways, means for feeding brush backs to the gripping means in advance of said stations, and means mounted on the carrier for intermittently rotating said sprockets to position a brush back held in the gripping means sequentially at the drilling station and then at the tufting station.

7. In a brush making machine having a drilling station including a drill to form holes in a brush back, a tufting station including a tufter to insert tufts into said holes and means for operating said drill and tufter to drill a hole in a brush back positioned at the drilling station while simultaneously inserting a tuft in a previously drilled hole in another brush back positioned at the tufting station, means for conveying brush backs to the drilling station and then to the tufting station comprising a carrier, means for moving the carrier in at least two directions substantially at right angles to each other, a pair of sprockets mounted in spaced relationship on the carrier for rotation in a single plane, a chain carried by the sprockets and having a portion passing in a linear path through the drilling station and the tufting station, a plurality of brush back gripping means on the chain, spaced parallel ways on the carrier extending along said path on both sides of the chain, guide means secured to the chain and riding in said ways, other ways mounted on the carrier in spaced parallel relationship to said path and adapted to guidingly receive a handle secured to the brush back, means for feeding brush backs to the gripping means in advance of said stations, and means mounted on the carrier for intermittently rotating said sprockets to position a brush back held in the gripping means sequentially at the drilling station and then at the tufting station.

8. In a brush making machine having a drilling station including a drill to form holes in a brush back, a tufting station including a tufter to insert tufts into said holes and means for operating said drill and tufter to drill a hole in a brush back positioned at the drilling station while simultaneously inserting a tuft in a previously drilled hole in another brush back positioned at the tufting station, means for conveying brush backs to the drilling station and then to the tufting station comprising a carrier, means for moving the carrier in at least two directions substantially at right angles to each other, a pair of sprockets mounted in spaced relationship on the carrier for rotation in a single plane, a chain carried by the sprockets and having a portion passing in a linear path through the drilling station and the tufting station, a plurality of blocks mounted on and spaced along the chain, a jaw carried by each block, a pair of spaced parallel guiding channels on the carrier extending along said path on both sides of the chain, guide means on each block adapted to ride in said channels, a guide way mounted on the carrier and adapted to guidingly receive a handle secured to the brush back, a hopper adapted to

contain a supply of brush backs and having a discharge opening located adjacent one of the sprockets where the chain is travelling there-around whereby a brush back fed from said discharge opening is gripped by the jaws as the chain enters said linear path after leaving said sprocket, a release station located adjacent the other sprocket and having means for receiving a brush back as it is released from the jaws as the chain travels in an arcuate path around said other sprocket, and a pneumatic piston and cylinder device connected to one of the sprockets for intermittently but rapidly rotating the sprockets to position a brush back sequentially at the drilling station and the tufting station and then to move the brush back to the release station.

9. In a brush making machine having a drilling station including a drill to form holes in a brush back, a tufting station including a tufter to insert tufts into said holes and means for operating said drill and tufter to drill a hole in a brush back positioned at the drilling station while simultaneously inserting a tuft in a previously drilled hole in another brush back positioned at the tufting station, means for conveying brush backs to the drilling station and then to the tufting station comprising a carrier, means for moving the carrier in at least two directions substantially at right angles to each other, a conveyor mounted on the carrier and provided with a plurality of brush back gripping means, a feeding station including a hopper adapted to contain a supply of brush backs and having a discharge opening, a pneumatic piston and cylinder device having a plunger located at said discharge opening and adapted to propel a brush back from the hopper and into the gripping means, means for intermittently moving and halting the conveyor to position a brush back held in the gripping means sequentially at the drilling station and the tufting station, and automatically operating timing means for actuating said operating means and said piston and cylinder device each time said conveyor is halted.

10. In a brush making machine having a drilling station including a drill to form holes in a brush back, a tufting station including a tufter to insert tufts into said holes and means for operating said drill and tufter to drill a hole in a brush back positioned at the drilling station while simultaneously inserting a tuft in a previously drilled hole in another brush back positioned at the tufting station, means for conveying brush backs to the drilling station and then to the tufting station comprising a carrier, means for moving the carrier in at least two directions substantially at right angles to each other, a pair of sprockets mounted in spaced relationship on the carrier for rotation in a single plane, a chain carried by the sprockets and having a portion passing in a linear path through the drilling station and the tufting station, a plurality of brush back gripping means on the chain, spaced parallel ways on the carrier extending along said path on both sides of the chain, guide means secured to the chain and riding in said ways, means for feeding brush backs to the gripping means in advance of said stations, a pneumatic piston and cylinder device mounted on the carrier, a ratchet wheel secured to one of the sprockets for rotating the same, an actuating member carrying a pawl to engage the ratchet and secured to the piston, and means operated in timed relationship with said operating means

75

for supplying air under pressure to said cylinder to rotate said sprockets intermittently to position a brush back held in the gripping means sequentially at the drilling station and then at the tufting station.

11. In a brush making machine having a drilling station including a drill to form holes in a brush back, a tufting station including a tufter to insert tufts into said holes and means for operating said drill and tufter to drill a hole in a brush back positioned at the drilling station while simultaneously inserting a tuft in a previously drilled hole in another brush back positioned at the tufting station, means for conveying brush backs to the drilling station and then to the tufting station comprising a carrier, means for moving the carrier in at least two directions substantially at right angles to each other, a pair of sprockets mounted in spaced relationship on the carrier for rotation in a single plane, a chain carried by the sprockets and having a portion passing in a linear path through the drilling station and the tufting station, a plurality of brush back gripping means on the chain, spaced parallel ways on the carrier extending along said path on both sides of the chain, guide means secured to the chain and riding in said ways, means for feeding brush backs to the gripping means in advance of said stations, a pneumatic piston and cylinder device mounted on the carrier, ratchet means secured to one of the sprockets for rotating the same, an actuating arm secured to the piston, a first pawl on the arm for engaging the teeth on the ratchet means for rotating the same with reciprocation of the piston, a second pawl on the arm positioned to engage said teeth after the ratchet means has been rotated by the first pawl to stop the rotation thereof, and means operated in timed relationship with said operating means for supplying air under pressure to said cylinder to rotate said sprockets intermittently to position a brush back held in the gripping means sequentially at the drilling station and then at the tufting station.

12. In a brush making machine having a frame, a rotary drill mounted on the frame for vertical reciprocation, means for rotating the drill, a tufter mounted on the frame for vertical reciprocation, and means for simultaneously reciprocating the drill and tufter to form a hole in a brush back positioned beneath the drill and to insert a tuft in a previously formed hole in a brush back positioned beneath the tufter, operating and conveying means comprising a carrier mounted on the frame for movement in at least two directions, a conveyor movably mounted on the carrier and adapted to carry a plurality of brush backs, a first and a second cam adapted to be rotated constantly during operation of the machine, a cam follower for each cam, means connecting the carrier with one of said cam followers and adapted to move the carrier in one of said directions, other means connecting the carrier with another of said cam followers and adapted to move the carrier in the other direction, said cams being adapted to cause movement of the carrier in at least one of said directions each time the drill and tufter are reciprocated to shift brush backs in said conveyor relative to said drill and tufter to drill a predetermined plurality of spaced holes in a brush back as it is positioned beneath the drill and to insert a tuft in each hole previously drilled in another brush back positioned beneath the tufter, means for moving the conveyor, and a third con-

15

stantly rotated cam having a cam follower connected to the last named moving means, said third cam being adapted upon the completion of the forming of said predetermined number of holes to cause movement of the conveyor to position other brush backs thereon beneath the drill and tufter.

13. In a brush making machine having a frame, a rotary drill mounted on the frame for vertical reciprocation, means for rotating the drill, a tufter mounted on the frame for vertical reciprocation, and means for simultaneously reciprocating the drill and tufter to form a hole in a brush back positioned beneath the drill and to insert a tuft in a previously formed hole in a brush back positioned beneath the tufter, operating and conveying means comprising a carrier mounted on the frame for movement in at least two directions, a conveyor movably mounted on the carrier and adapted to carry a plurality of brush backs, a cam shaft, motor means for constantly rotating said shaft during operation of the machine, a first and a second cam fixed to said shaft, a cam follower for each cam, means connecting the carrier with one of said cam followers and adapted to move the carrier in one of said directions, other means connecting the carrier with another of said cam followers and adapted to move the carrier in the other direction, said cams being adapted to cause movement of the carrier in at least one of said directions each time the drill and tufter are reciprocated to shift brush backs in said conveyor relative to said drill and tufter to drill a predetermined plurality of spaced holes in a brush back as it is positioned beneath the drill and to insert a tuft in each hole previously drilled in another brush back positioned beneath the tufter, means for moving the conveyor, and a third cam fixed to said shaft having a cam follower connected to the last named moving means, said third cam being adapted upon the completion of the forming of said predetermined number of holes to move the conveyor to position other brush backs thereon beneath the drill and tufter.

14. In a brush making machine having a frame, a rotary drill mounted on the frame for vertical reciprocation, means for rotating the drill, a tufter mounted on the frame for vertical reciprocation, and means for simultaneously reciprocating the drill and tufter to form a hole in a brush back positioned beneath the drill and to insert a tuft in a previously formed hole in a brush back positioned beneath the tufter, operating and conveying means comprising a carrier mounted on the frame for movement in at least two directions, a conveyor movably mounted on the carrier and adapted to carry a plurality of brush backs, a cam shaft, motor means for constantly rotating said shaft during operation of the machine, a first and a second cam fixed to said shaft, a cam follower for each cam, means connecting the carrier with one of said cam followers and adapted to move the carrier in one of said directions, other means connecting the carrier with another of said cam followers and adapted to move the carrier in the other direction, said cams being adapted to cause movement of the carrier in at least one of said directions each time the drill and tufter are reciprocated to shift brush backs in said conveyor relative to said drill and tufter to drill a predetermined plurality of spaced holes in a brush back as it is positioned beneath the drill and to insert a tuft in each hole previously drilled in another

brush back positioned beneath the tufter, a pneumatic piston and cylinder device for moving the conveyor, valve means for operating the device, and a third cam fixed to said shaft having a cam follower connected to said valve means, said third cam being adapted upon the completion of the forming of said predetermined number of holes to operate said valve to move the conveyor to position other brush backs thereon beneath the drill and tufter.

15. In a brush making machine having a frame, a rotary drill mounted on the frame for vertical reciprocation, means for rotating the drill, a tufter mounted on the frame for vertical reciprocation, and means for simultaneously reciprocating the drill and tufter to form a hole in a brush back positioned beneath the drill and to insert a tuft in a previously formed hole in a brush back positioned beneath the tufter, operating and conveying means comprising a carrier mounted on the frame for movement in at least two directions, a conveyor movably mounted on the carrier and adapted to carry a plurality of brush backs, a cam shaft, motor means for constantly rotating said shaft during operation of the machine, a first and a second cam fixed to said shaft, a cam follower for each cam, means connecting the carrier with one of said cam followers and adapted to move the carrier in one of said directions, other means connecting the carrier with another of said cam followers and adapted to move the carrier in the other direction, said cams being adapted to cause movement of the carrier in at least one of said directions each time the drill and tufter are reciprocated to shift brush backs in said conveyor relative to said drill and tufter to drill a predetermined plurality of spaced holes in a brush back as it is positioned beneath the drill and to insert a tuft in each hole previously drilled in another brush back positioned beneath the tufter, a pneumatic piston and cylinder device, a ratchet wheel connected to the conveyor for moving the same, an actuating member carrying a pawl to engage the ratchet and secured to the piston, valve means for operating the device, and a third cam fixed to said shaft having a cam follower connected to said valve means, said third cam being adapted upon the completion of the forming of said predetermined number of holes to operate said valve to move the conveyor to position other brush backs thereon beneath the drill and tufter.

16. In a brush making machine having a frame, a rotary drill mounted on the frame for vertical reciprocation, means for rotating the drill, a tufter mounted on the frame for vertical reciprocation, and means for simultaneously reciprocating the drill and tufter to form a hole in a brush back positioned beneath the drill and to insert a tuft in a previously formed hole in a brush back positioned beneath the tufter, operating and conveying means comprising a guideway mounted on the frame, a member slidably in said guideway and carrying a second guideway positioned at right angles to the first guideway, a carrier member slidably in said second guideway, a conveyor mounted on the carrier and adapted to carry a plurality of brush backs, a cam shaft, motor means for constantly rotating said shaft during operation of the machine, a first and a second cam fixed to said shaft, a cam follower for each cam, means connecting the carrier member with one of said cam followers to move the carrier along said second guideway, a crank connecting the member with another of

said cam followers to move the member along said first guideway, said cams being adapted to cause movement of at least one of said members each time the drill and tufter are reciprocated to shift brush backs in said conveyor relative to said drill and tufter to drill a predetermined plurality of spaced holes in a brush back as it is positioned beneath the drill and to insert a tuft in each hole previously drilled in another brush back positioned beneath the tufter, means for moving the conveyor, and a third cam fixed to said shaft having a cam follower connected to the last named moving means, said third cam being adapted upon the completion of the forming of said predetermined number of holes to move the conveyor to position other brush backs thereon beneath the drill and tufter.

17. In a brush making machine having a frame, a rotary drill mounted on the frame for vertical reciprocation, means for rotating the drill, a tufter mounted on the frame for vertical reciprocation, and means for simultaneously reciprocating the drill and tufter to form a hole in a brush back positioned beneath the drill and to insert a tuft in a previously formed hole in a brush back positioned beneath the tufter, operating and conveying means comprising a guideway mounted on the frame, a member slidale in said guideway and carrying a second guideway positioned at right angles to the first guideway, a carrier member slidale in said second guideway, a conveyor mounted on the carrier and adapted to carry a plurality of brush backs, a cam shaft, motor means for constantly rotating said shaft during operation of the machine, a first and a second cam fixed to said shaft, a cam follower for each cam, means connecting the carrier member with one of said cam followers to move the carrier along said second guideway, a crank connecting the member with another of said cam followers to move the member along said first guideway, said cams being adapted to cause movement of at least one of said members each time the drill and tufter are reciprocated to shift brush backs in said conveyor relative to said drill and tufter to drill a predetermined plurality of spaced holes in a brush back as it is positioned beneath the drill and to insert a tuft in each hole previously drilled in another brush back.

18. In a brush making machine having a frame, a rotary drill mounted on the frame for vertical reciprocation, means for rotating the drill, a tufter mounted on the frame for vertical reciprocation, and means for simultaneously reciprocating the drill and tufter to form a hole in a brush back positioned beneath the drill and to insert a tuft in a previously formed hole in a brush back positioned beneath the tufter, operating and conveying means comprising a guideway mounted on the frame, a member slidale in said guideway and carrying a pair of spaced guideways positioned parallel to each other and at right angles to the first guideway, a carrier member slidale in said pair of guideways, a conveyor mounted on the carrier and adapted to carry a plurality of brush backs, automatically operating means for feeding blank brush backs to and for removing drilled and tufted brush backs from the conveyor, a cam shaft, motor means for constantly rotating said shaft during operation of the machine, a first and a second cam fixed to said shaft, a cam follower for each cam, means connecting the carrier with one of said cam followers to move the carrier member along said

pair of guideways, a crank connecting the member with another of said cam followers to move the member along said first named guideway, said cams being adapted to cause movement of at least one of said members each time the drill and tufter are reciprocated to shift brush backs in said conveyor relative to said drill and tufter to drill a predetermined plurality of spaced holes in a brush back as it is positioned beneath the drill and to insert a tuft in each hole previously drilled in another brush back.

19. In a brush making machine having a frame, a drilling station including a drill for forming holes in a brush back and a tufting station including a tufter for inserting tufts into the holes, means for moving brush backs into a plurality of predetermined positions at each station comprising a guideway on the frame, a member slidale on said guideway and carrying a pair of spaced parallel guideways aligned at substantially right angles to the guideway, a carrier slidale on said pair of guideways, means on the carrier for holding a brush back at the drilling station and for holding another brush back at the tufting station, a rotatably mounted cam, a cam follower riding on the cam, crank means connecting the cam follower to the member for sliding the member along said first named guideway, a second rotatably mounted cam, a second cam follower riding on the second cam, means secured to the carrier and defining an elongated slot extending parallel to the first mentioned guideway, a pin slidale in said slot and engaging the sides thereof, said pin being connected to said second cam follower for sliding the carrier along said pair of guideways, and means for rotating the cams.

20. Apparatus of the character described in claim 19 in which said crank means comprises a disc rotatably mounted on the frame, a plate carried by the member and having an elongated opening therein, a bearing post on the disc, a bushing eccentrically mounted on the post and engaging the sides of the opening, means for securing the bushing to the post in any one of a plurality of positions eccentric thereto, and means connecting the disc to said first cam follower.

21. In a brush making machine having a frame, a drilling station including a drill for forming holes in a brush back and a tufting station including a tufter for inserting tufts in the holes, means for moving brush backs into a plurality of predetermined positions at each station comprising a guideway mounted for vertical movement on the frame and positioned below said stations, a member slidale on said guideway and carrying a second guideway aligned at substantially right angles to the first named guideway, a carrier slidale on said second guideway, means on the carrier for holding a brush back at the drilling station and for holding another brush back at the tufting station, a rotatably mounted cam, a cam follower riding on the cam, means connecting the cam follower to the member for sliding the member along said first guideway, a second rotatably mounted cam, a second cam follower riding on the second cam, other means connecting the second cam follower to the carrier for sliding the carrier along said second guideway, means for securing a camming surface to said other connecting means, said camming surface being adapted to contact the member to move the same vertically with movement of the last-mentioned connecting means, and means for rotating the cams.

22. In a brush making machine having a frame, a drilling station including a drill for forming holes in a brush back and a tufting station in-

cluding a tufter for inserting tufts in the holes, means for moving brush backs into a plurality of predetermined positions at each station comprising a plurality of supporting posts mounted for vertical longitudinal movement on the frame, a guideway supported by the posts and positioned below said stations, a member slidable on said guideway and carrying a second guideway aligned at substantially right angles to the first named guideway, a carrier slidable on said second guideway, means on the carrier for holding a brush back at the drilling station and for holding another brush back at the tufting station, a rotatably mounted cam, a cam follower riding on the cam, means connecting the cam follower to the member for sliding the member along said first guideway, a second rotatably mounted cam, a second cam follower riding on the second cam, other means connecting the second cam follower to the carrier for sliding the carrier along said second guideway, camming means secured to said member and to said other connecting means and cooperating to move the member vertically with movement of the last mentioned connecting means, and means for rotating the cams.

23. Apparatus of the character described in claim 22 in which said camming means includes a member having a curved upper surface and secured to said other connecting means, and a button secured to the member and adapted to ride on said surface.

24. In a brush making machine having a frame, means for forming a plurality of holes in a brush back, means for inserting tufts into said holes, and means for controlling a tuft guard for bending inserted tufts to a non-interfering position during the insertion of another tuft in a brush back, neutralizing means for the tuft guard comprising a rotatably mounted drive shaft for moving the tuft guard, means for oscillating the shaft, a member secured to the shaft and provided with a flattened portion on the edge thereof, an arm mounted on the frame for pivotal movement about an axis of rotation parallel to the axis of rotation of the shaft, said arm having a flat face adapted to contact said flattened portion, and resilient means urging said face into contact with said portion to rotate the member to a position in which said portion along substantially its entire length is in contact with said face.
